US0D1066786S

(12) **United States Design Patent** (10) **Patent No.:** **US D1,066,786 S**
(45) **Date of Patent:** **** Mar. 11, 2025**

(54) **LIGHT**

(71) Applicant: **Wisewell Holdings**, Grand Cayman (KY)

(72) Inventors: **Sami Khoreibi**, Grand Cayman (KY); **Sebastien Wakim**, Grand Cayman (KY); **Hing Wah Tsang**, Grand Cayman (KY); **Paul Daniel Farrugia**, Grand Cayman (KY)

(73) Assignee: **Wisewell Holdings**, Grand Cayman (KY)

(**) Term: **15 Years**

(21) Appl. No.: **29/831,292**

(22) Filed: **Mar. 18, 2022**

(30) **Foreign Application Priority Data**

Dec. 31, 2021 (CN) 202130883156.X

(51) **LOC (15) Cl.** **26-05**

(52) **U.S. Cl.**

USPC **D26/149**
